By Paul Paul

ATTORNEYS

UNITED STATES PATENT OFFICE.

AUGUST W. SKOG, OF MINNEAPOLIS, MINNESOTA.

TENT.

Application filed April 3, 1922. Serial No. 549,812.

To all whom it may concern:

Be it known that I, AUGUST W. SKOG, a citizen of the United States, resident of Minneapolis, county of Hennepin, State of Minnesota, have invented certain new and useful Improvements in Tents, of which the following is a specification.

The object of my invention is to provide a tent composed of separable frame sections which can be readily taken apart and set up and when in knock-down form capable of being bundled compactly and stored on the running board or tonneau of an automobile for convenient transportation from place to place.

A further and particular object is to provide the canvas cover of the tent in separable sections so that instead of being rolled up in one bundle and completely filling the tonneau, or some other part of the car, the canvas can be distributed in different places and considerable space in the car left for other articles, which ordinarily would be entirely occupied by the folded tent.

25 A further object is to provide a tent so constructed that it will be practically impervious to wind and moisture.

The invention consists generally in various constructions and combinations, all as 30 hereinafter described and particularly pointed out in the claims.

In the accompanying drawings forming part of this specification,

Figure 1 is a perspective view of a tent 35 embodying my invention,

Figure 2 is a similar view of the frame or skeleton before the canvas is applied,

Figure 3 is a detail sectional view illustrating the manner of securing the canvas 40 panels to the end frames,

Figure 4 is a detail view of one of the hooks to which the canvas panels are connected.

Figure 5 is a detail sectional view showing 45 the manner of mounting the ridge pole in the end frame or gables of the tent,

Figure 6 is a detail view showing the preferred construction of the gable cap and the means for attaching the guy rope thereto.

50 In the drawing, 2 and 3 represent the rafters at one end of the tent, a similar construction being provided at the other end, which I do not illustrate, as it is not necessary for a clear understanding of the

tent construction. The upper ends of the 55 rafters are beveled, as at 4, to abut one another, and a triangular cap 5 is fitted over the abutting ends of the rafters and has holes 6 therein to receive a spindle 7 on the end of the ridge pole 8. This spindle projects through the cap and the ridge pole has freedom of movement therein to allow for outward movement of the rafters when the guy ropes are tightened. The cap 5 has a depending member 5^a having a hole 65 9 therein in which the guy rope 10 is secured, the other end being fastened to a peg 11 in the ground in the usual manner. When these guy ropes are tightened, the rafters will be pulled apart and the roof 70 panels drawn taut, as will hereinafter appear.

The rafters have boxes 12 at their lower ends provided with sockets to receive the upper ends of posts 13 which form the 75 corners of the tent, and correspond in height to the wall panels, said boxes being angled in form to provide a connecting means between the upper ends of the posts and the lower ends of the rafters, and, if preferred, 80 these boxes may be secured by pins or nails to the ends of the posts and the rafters.

Intermediate to the upper and lower ends of the rafters I provide boxes 14 having 85 sockets 15 therein to receive the upper ends of posts 16 which form the uprights on each side of the doorway. These posts are readily removable from the sockets, as well as the posts 13, so that the frame of the tent can be easily and quickly reduced to a 90 knock-down form and compactly bundled for transportation on the running board or other part of an automobile. The post 13 and the rafters are provided with a series

of hooks 17 having shanks 18 which project through the rafters and posts and secured therein by suitable means, such as nuts 19. These hooks serve the double function of holding the upright end wall panels 20, the side wall panels 21 and the roof panels 22 in place. The manner of mounting 95 the end and side wall panels is illustrated in Figure 3, wherein 23 represents an eyelet or grommet inserted in the canvas and adapted to receive the hooks sliding thereon to a point close against the surfaces of the posts, while the projecting ends of

the hooks serve as a means for connecting 100 105 the panels to the posts.

the roof panels to the rafters, said roof panels having grommets therein corresponding to those in the side and end wall panels.

Instead of making the roof sections in one piece, which would be too bulky to be rolled and packed in one place on a car, I divide these sections into a series of longitudinal panels and for the purpose of making joints between these panels rain and wind proof, I prefer to provide brackets 24 secured to the upper edges of the rafters and having straight sections 25 at right angles to the edges of the rafters to which sections bars 26 are connected at each end of the tent with their inner endslapping by each other and held inlapping relation by guide loops 27. These loops permit the bars to slide one upon another and adjust themselves as the rafters are pulled apart by the tension of the guy ropes in tightening or tensioning the roof panels. These straight sections 25 of the brackets and the bars connecting them lengthwise of the tent cause offsets substantially right angled to be formed in the roof panels, as indicated in Figure 1, such offsets being several inches from the edge of the panel and positively preventing rain or wind from blowing into the tent between the lapping edges of the panels.

In setting up the tent, the bars comprising the skeleton frame are first raised with the post supporting the rafters and then the rails connecting the brackets of the rafters are put in place and secured by suitable means, such as pins or nails, capable of convenient removal, and when this has been done, the canvas panels are put in place, the side and end walls first, with the pins in the posts, and rails enter the grommets in the panels, and then over the edges of the wall panels the roof sections are stretched and engaged with the hooks at the ends, the lower edge of the upper roof panels overlapping the upper edge of the panel next beneath. When the ridge pole has been put in place, the guy ropes may be tightened, pulling the rafters at the ends of the tent apart and putting the roof panels under tension. A suitable roll flap 28 is provided for closing the tent doorway.

In taking down the tent, the roof panels can be first unhooked and rolled separately, if preferred, and the wall panels may then be removed and also rolled to make small separate parcels for distribution in different parts of the car, thus allowing the tent to be packed for transportation without filling the seating space of the tonneau, where usually it has been necessary to place the folded tent. In this way I am able to effect a considerable economy in transportation

space. The rafters and posts may be bundled together and carried on the running board or any other suitable place.

65

I claim as my invention:

1. A tent comprising a frame having rafters and supporting posts, end and side wall panels mounted on said posts and rafters and roof panels having their ends connected to said rafters over the upper portions of said wall panels, a ridge pole connecting the rafters and means for pulling the rafters outwardly to tension the roof panels.

75 2. A tent comprising a frame having rafters, a ridge pole between them and posts supporting said rafters, rails connecting said rafters intermediate to their ends and roof panels stretched over said rails between said rafters with their abutting longitudinal edges in lapping relation, said rails forming offsets or angles in said panels.

80 3. A tent comprising a frame, a roof composed of a series of panels stretched over said frame, with lapping edges and means for forming offsets in the lapping surfaces of said panels.

85 4. In a tent, rafters and supporting posts therefor, brackets mounted on said rafters, rails connecting said brackets between the rafters at the ends of the tent and roof panels stretched between said rafters and over said brackets and rails and having offsets or angles formed therein by said brackets and rails.

90 5. A tent comprising a frame having rafters and supporting posts and hooks mounted in said rafters and posts, wall panels having grommets to receive said hooks and roof panels having lapping edges stretched between said rafters and having grommets to receive said hooks and covering and concealing the upper edges of said wall panels.

95 6. A tent comprising end rafters and supporting posts therefor, a ridge pole having its ends loosely mounted at the juncture of the pair of rafters for freedom of longitudinal movement with respect thereto, guy ropes connected with said rafters for separating the opposite pairs and a flexible wall and roof covering.

100 7. A tent comprising a ridge pole, upright posts, end rafters supported thereby and having bearings for said pole and movable back and forth with respect thereto, a roof covering connecting said rafters over said ridge pole, and guy ropes connected with said rafters for drawing them outwardly and tightening said covering.

105 In witness whereof, I have hereunto set my hand this 31st day of March, 1922.

AUGUST W. SKOG.
